2,001,410

AIR CONDITIONING APPARATUS

Charles B. Cook, Los Angeles, Calif.

Application April 2, 1934, Serial No. 718,619
Renewed April 12, 1935

11 Claims. (Cl. 257—9)

This invention relates to air conditioning apparatus.

The general object of the invention is to provide an improved compact and efficient structure for use in conditioning large volumes of air.

Another object of the invention is to provide a novel combined air conditioning apparatus and heater.

A further object of the invention is to provide an improved rotary member for use in an air conditioning apparatus.

Another object of the invention is to provide a novel means for controlling the flow of air through an air conditioning apparatus.

Other objects and the advantages of this invention will be apparent from the following description taken in connection with the accompanying drawings wherein:

Fig. 1 is a top plan view of my device with parts broken away;

Fig. 2 is a section taken on line 2—2 of Fig. 1;
Fig. 3 is a section taken on line 3—3 of Fig. 2;
Fig. 4 is a wiring diagram;

Fig. 5 is a fragmentary section taken on line 5—5 of Fig. 1 showing means to simultaneously control the shutters;

Fig. 6 is an elevation showing the thermostat; and,

Fig. 7 is a sectional detail showing a modification of my invention.

Referring to the drawings by reference characters I have shown my invention as embodied in an air conditioning apparatus which is indicated generally at 10. As shown the device includes a body 11 having legs 12 thereon at one end. At the other end the body is supported on a fire box 13 which includes a bottom 14, end walls 15 and side walls 16.

The body consists of a suitable bottom 17, sides 18, end walls 19, hinged top 20 which includes a pivoted closure 20'. At one end the body is provided with a centrifugal blower 21 which is driven by a motor 22. An inlet duct 23 extends from the blower and is connected to an outer duct 24 with a removable screen 25 between the ducts.

A partition member 26 partially surrounds the blower and from one end of the partition 26 a diagonal partition 27 extends to the top 20.

A second partition member indicated generally at 28 includes a portion 29 parallel to the portion 27, a horizontal portion 30 and a vertical portion 31. The portion 29 is joined by a curved portion 32 to a horizontal portion 33, which joins another

curved portion 34 and merges into an upwardly extending portion 35.

The rear wall 19 includes a horizontal portion 36 which is in line with the horizontal portion 30.

The bottom 17 is continued into a curved portion 37, thence into a vertical portion 38 which is parallel to the portion 35. The portions 35 and 38 are joined by plane portions 39 and 40, as shown, to form a duct 41. The top at one end of the hinged closure 20 is curved, as at 42, and then extends upwardly as at 43 parallel to the outside of the wall 35. The portion 36 is curved upwardly as at 44 to a straight portion 45 which is parallel to but is spaced outwardly from the vertical portion 38.

The portions 43 and 45 are joined by plane portions 46 and 47, which extend parallel to and are spaced outwardly from the portions 39 and 40. It will thus be seen that there is a duct 48 which is arranged outside of and surrounding the duct 41 and that the duct 41 communicates with the passageway, which I have designated A and which is a heat transfer chamber and is between the bottom 17 and the portion 33 and that the duct 48 communicates through a chamber B with a passageway C.

Within the chamber B I mount a shaft 49 which has a sprocket 50 thereon which is driven by a chain 51 from a sprocket 52, which is on a shaft 53 driven by the motor 22.

On the shaft 49 I arrange a plurality of disks 54 and spacers 55. The disks 54 are peripherally spaced as at 55'. The disks 54 are arranged between the walls 19 and 31 and between the walls 18 which are joined to these walls 19 and 31 and to the bottom 33 to form a tank D which in operation contains water in which the lower portions of disks 54 are immersed. The upper portions of the disks 54 are positioned between walls 56 and 57 which together with the top 20 forms the chamber B.

The bottom of the tank D is perforated and receives a plurality of tubes 58 which extend downwardly and pass through the bottom 17. These tubes 58 afford communication between the tank D and a tank E which is in the upper portion of the fire-box 13. A plurality of fire-tubes 59 pass from the fire-box 13 through the tank E to a heater 60 which extends horizontally and which communicates with a vertically extending stack 61.

The tubes 58 have a plurality of heat transfer fins 62 thereon. The tubes 58 and the fins 62 form a heat exchange chamber while the chamber B provides a humidifying chamber.

- The amount of air passing into the humidifying chamber B is controlled by a plurality of shutters 63 which are pivoted as at 64 and which are operably connected together by a member 65 so that they move in unison. Similarly, the exit from the humidifying chamber B is controlled by shutters 66, which are pivoted as at 67 and which are linked together by a member 68 for movement in unison.
- Passage through the conduit A is controlled by a plurality of shutters 69 which are pivoted as at 70 and which are connected by a member 71 to move in unison.
- In order to return a portion of the air which has passed through the humidifying chamber B back to the inlet duct 23 I provide a pipe 72 which at one end communicates with the inlet duct 23 and which communicates at the other end with an elbow 73 which enters the humidifying chamber B adjacent the shutters 66.
- The pipe 72 includes a damper 74, which has a shaft 75 on which arm 76 is mounted. The arm 76 includes a slot 77 in which a pin 78 on a link 79 is mounted. The link 79 is pivotally connected to another link 80 which is secured on one of the shafts 67 of the shutters 66 and the construction is such that when the link 80 is rocked to close the shutters 66 the damper 74 is opened and when the shutters 66 are opened the damper is closed.
- In order to rock the link 80 this link is connected to a link 81, which is connected to the core 82 of a reversible solenoid device which includes coils 83 and 84. The solenoid device is adapted to be operated by a thermostat which includes a thermal responsive arm 85, which is adapted in one position to engage a contact 86 and in another position engages a contact 87. The arm 85 is connected by a lead 88 to a battery 89, which is in turn connected by a lead 90 to a pivoted contact arm 91 which is adapted to engage spaced contacts 92 and 93. The contact 92 is connected by a wire 94 to the coil 84 and the coil 84 is connected by a wire 95 to the contact 86, the contact 93 is connected by a wire 96 to the coil 83 which is connected by a wire 97 to the contact 87.
- Construction is such that when the circuit is completed through the arm 85 the contact 86, and arm 91 and contact 92 the coil 84 will be energized, thereby moving the core 82 and rocking the arm 80, also the arm 91 will move so that it engages the contact 93.
- When the temperature changes so that the arm 85 engages the contact 87 the core 83 will be energized thus rocking the arm 80 in a reverse direction.
- My apparatus may function either for heating or cooling and I shall first describe it in operation as a cooling unit.
- Warm air of normal humidity is drawn in through the external inlet duct 24 through the screen 25 and duct 23 to the blower 21 whence it is forced towards the humidifying chamber B and the heat transfer chamber A. The amount of air flowing through the humidifying chamber B is controlled by the shutters 66, the shutters 69 being fully opened.
- The disks 54 are rotated by the blower motor as described. Thus the surface of the disks within the humidifying chamber B are kept wet and a large area of water surface is exposed to the air current within providing opportunity for maximum evaporation. Evaporation occurs and this evaporation from the surface of the water on the plates 54 causes the remaining water to drop in temperature and will mix with and reduce the temperature of the water in tank D, to approximately the "wet bulb" temperature of the incoming air.
- The rotation of the disks 54 causes circulation of the water in tank D, tubes 58 and fire tube chamber E. The air exhausted from the humidifying chamber has an increased moisture content and a reduced temperature. The level of the water in the tank C is maintained constant by means of float valve 100 shown as arranged in an auxiliary tank 101 which has a pipe 102 communicating with the tank D. The tank 101 has an overflow 103.
- The amount of air flowing from the blower to the heat transfer chamber A is controlled by the shutters 69 which are, for cooling, normally open. As the air passes around the tubes 58 and the fins 62 heat is transferred through the tubes and fins to the water which has been previously cooled as explained above.
- The cool air discharged from the heat exchange chamber 27 is conducted to the area to be cooled by the duct 39. The duct 39 is within the duct 48 and is therefore surrounded by the cooled "wet" air discharged from humidifying chamber B. Thus the cold air in duct 39 may be conducted with maximum efficiency.
- When the device is used as a heating unit the blower again draws air and discharges it as described. The shutters 63 however may be now in their closed position which position does not completely obstruct passageway and a small flow of air is permitted into the humidifying chamber B. The shutters 66 are now completely closed and the air passes into the pipe 72 which conducts humidified air back to the intake duct 23 of the blower. As described the pipe 72 has a damper 74 which is coupled with the shutters 66 so that when the shutters 66 are closed the damper is in its open position and vice versa. The open position of the damper may be adjusted to control the amount of humidified air returning to the intake duct 23.
- The air flows through the shutters 69 into the heat exchange chamber A where it absorbs heat from the tubes and fins which are heated by the water. A burner 105 in the fire box 13 heats the water in the chamber E the gaseous products of combustion being carried off through the heater 60 and stack 61. The air discharged from the heat exchange chamber is conducted through the duct 41.
- The air stream from the blower 21 strikes the disks 54 so that the tendency is to cause the disks to rotate counter-clockwise but the chain 51 is driven so that the disks rotate clockwise. This causes the water to pile up at the left side of the device in Fig. 2 and thus a head is created causing the circulation to be down at the left of the radiator in Fig. 2 and up at the right. This presents the coldest water at the left of the radiator and therefor the air passing over the radiator is gradually cooled. In heating the hottest water is at the right end of the tank E in Fig. 2 and the result is a circulation which is forced as well as thermal and wherein the circulation is clockwise. The circulation it will thus be seen is in the same direction whether the device is used in heating or for cooling. It will be understood that the column of air passes substantially parallel to the disks 54 although the angle may vary. I thus avoid passing the air column through apertures in the disks.
- In the modification of my invention shown in 75

Fig. 7 I have substituted a water chamber 106 for the fire box 13. This water chamber 106 is supported on legs 107. This water chamber is installed when my invention is to be used only for cooling but the chamber 107 may be interchangeable with the fire tube chamber 13 before described.

From the foregoing it will be apparent that I have invented a novel air conditioning apparatus which can be economically manufactured and which is highly efficient in use.

Having thus described my invention, I claim:

1. In a device of the class described, a water circulation system including a member adapted to have its surface wetted, means to supply water to said surface, a radiator, means whereby water from said surface passes to said radiator, means to pass a column of air over the wetted surface to partially evaporate the wetted surface whereby the remainder of water on the surface is cooled before it passes to the radiator. 10
2. In an air conditioning apparatus, a receptacle having an air conditioning chamber therein, a tank in said chamber, a blower having an inlet, means to drive said blower, a passageway extending from said blower to said chamber, means to control communication through said passageway, a pipe leading from said chamber back to said inlet, a damper in said pipe and means whereby said control means operates said damper. 20
3. In an air conditioning apparatus, a receptacle having a humidifying chamber therein, and having a heat exchange chamber therein, a tank in said air humidifying chamber, said tank having pipes communicating therewith, said pipes passing to said heat exchange chamber, a plurality of spaced members adapted to be wetted by water in said tank, a blower, an inlet to said blower, means to drive said blower, a passageway extending from said blower to said humidifying chamber, a duct leading from said humidifying chamber, a second passageway leading from said blower to said heat exchange chamber, a second duct leading from said heat exchange chamber, said second duct being disposed within and surrounded by said first duct. 30
4. In an air conditioning apparatus, a humidifying chamber and heat exchange chamber, a tank in said air conditioning chamber, said tank having pipes communicating therewith, said pipes passing through said heat exchange chamber, a plurality of spaced members arranged to be wetted by water in said tank, a blower, means to drive said blower, a passageway extending from said blower to said humidifying chamber, a duct leading from said humidifying chamber, a passageway leading from said blower to said heat exchange chamber and a duct leading from said heat exchange chamber. 40
5. In an air conditioning device an air blower, means to drive said blower, a humidifying chamber, a heat transfer chamber, a water reservoir associated with said humidifying chamber, a plurality of disks mounted to rotate within said humidifying chamber and said water reservoir, means to rotate said disks, a radiator associated with said heat transfer chamber, a water tank associated with said radiator, means to circulate water from said water reservoir through said radiator and tank, means to conduct air from said blower to said humidifying chamber, means to conduct air from said blower to said heat transfer chamber, and means to control the flow of air through each chamber. 50
6. In an air conditioning device an air blower, means to drive said blower, a humidifying chamber, a heat transfer chamber, a water reservoir mounted below said humidifying chamber, a plurality of disks mounted to rotate within said humidifying chamber and in said water reservoir, means to rotate said disks, a radiator mounted within said heat transfer chamber, a water tank adjacent one end of said radiator, means to circulate water from said water reservoir through said radiator and tank back to said reservoir, a fire box associated with said water tank, means to conduct air from said blower to said humidifying chamber, means to conduct air from said blower to said heat transfer chamber, and means to control the flow of air through each chamber. 60
7. In an air conditioning apparatus, a humidifying chamber and a heat exchange chamber, a tank in said air humidifying chamber, said tank having pipes communicating therewith, said pipes passing through said heat exchange chamber, a shaft disposed adjacent said humidifying chamber, a plurality of spaced disks on said shaft and arranged to be wetted by water in said tank, means to rotate said shaft, a blower, means to drive said blower, a passageway extending from said blower to said humidifying chamber, means to control communication through said passageway, a duct leading from said humidifying chamber, a passageway leading from said blower to said heat exchange chamber means to control the passage through said last mentioned passageway and a duct leading from said heat exchange chamber. 70
8. In an air conditioning apparatus a heat transfer chamber, a water vaporizing chamber, an air blower, an inlet duct to said blower and air passage leading from the exhaust of said blower to said heat transfer chamber, another air passage leading from the exhaust of the blower to said water vaporizing chamber, a water reservoir adjacent the bottom of said water vaporizing chamber, a plurality of disks mounted to rotate partially submerged in water in said water reservoir the exposed portion of said disks extending upward into said water vaporizing chamber, means to rotate the disks, a radiator mounted within said heat transfer chamber and coupled on one side to said water reservoir and at another side to a water tank, means to circulate water from said water reservoir through said radiator to said tank and back to the water reservoir, a feed back duct leading from said water vaporizing chamber to said blower inlet duct and means to control the flow of air through said feed back duct. 80
9. In an air conditioning apparatus, a humidifying chamber, a heat exchange chamber, a tank in said humidifying chamber, said tank having pipes communicating therewith, said pipes passing through said heat exchange chamber, a tank below said heat exchange chamber, said pipes communicating with said tank, means to heat said last mentioned tank, a shaft in said humidifying chamber, a plurality of spaced disks on said shaft, said disks being adapted to turn in and to be wetted by water in said first mentioned tank, means to rotate said disks, a blower in said receptacle, means to drive said blower, a passageway extending from said blower to said humidifying chamber, means to control communication through said passageway, a duct leading from said humidifying chamber, means to control passage from said humidifying chamber. 90

to said duct, a passageway leading from said blower to said heat exchange chamber, means to control the passage through said last mentioned passageway and a duct leading from said heat exchange chamber.

10. In an air conditioning apparatus a heat transfer chamber, a water vaporizing chamber, an air blower, an inlet duct to said blower and air passage leading from the exhaust of said blower to said heat transfer chamber, another air passage leading from the exhaust of the blower to said water vaporizing chamber, a water reservoir adjacent the bottom of said water vaporizing chamber, a plurality of disks mounted 15 to rotate partially submerged in water in said water reservoir, the exposed portion of said disks extending upward into said water vaporizing chamber, means to rotate the disks, a radiator mounted within said heat transfer chamber and 20 coupled on one side to said water reservoir and at another side to a water tank, means to circulate water from said water reservoir through said radiator to said tank and back to the water reservoir, means to heat the water in said tank, a feed back duct leading from said water vaporizing chamber to said blower inlet duct, means to 25 control the flow of air through said heat transfer chamber, means to control the flow of air through said water vaporizing chamber, means to control the flow of air out of said water vaporizing chamber, and means associated with said last mentioned means to control the flow of air through said feed back duct.

11. In an air conditioning apparatus, a receptacle having a humidifying chamber therein, and having a heat exchange chamber therein, a tank in said air humidifying chamber, said tank having pipes communicating therewith, said pipes passing through said heat exchange chamber, a second tank below said heat exchange chamber, said pipes communicating with said second tank, means to heat said second tank, a shaft disposed adjacent to said first mentioned tank, a plurality of spaced disks on said shaft, said disks being adapted to turn in and to be wetted by water in said first mentioned tank, means to rotate said disks, a blower in said receptacle, an inlet to said blower, means to drive said blower, a passageway extending from said blower to said humidifying chamber, means to control communication through said passageway, a pipe leading from said humidifying chamber to said inlet, a damper in said pipe, means whereby said control means operates said damper, a duct leading from said humidifying chamber, means to control passage from said humidifying chamber to said duct, a passageway leading from said blower to said heat exchange chamber means to 25 control the passage through said last mentioned passageway, a duct leading from said heat exchange chamber, said second duct being disposed within and surrounded by said first duct.

CHARLES B. COOK.
